ADVERTISING CARD OR SIGN

George S. Rossi, New York, N. Y., assignor to
 Beaverite Products, Inc., Beaver Falls, N. Y., a
 corporation of New York

Application May 17, 1938, Serial No. 208,453

10 Claims. (Cl. 40—138)

This invention relates to cards or signs used for advertising and more particularly street car advertising.

The general object of the invention is to provide loosely mounted clearly visible movable parts which will attract attention when caused to move to and fro under vibratory action.

Other objects and advantages of the invention will be apparent as the specification is considered with the accompanying drawing, in which:

Figure 1 is a front view of the invention;

Figure 2 is a bottom or lower edge view of the same;

Figure 3 is a section taken on the line 3—3 of Figure 1;

Figure 4 is a section on the line 4—4 of Figure 3.

Referring more particularly to the drawing 1 denotes an advertising card adapted for insertion in the advertising space with which street cars and busses are generally provided. The card 1 is preferably made of relatively heavy or strong card board or paper or other suitable material to which printing and the like may be readily applied. In the present embodiment of my invention the front face 2 of the card 1, bears the face 3 of a clown, however the face of a beautiful woman or an animal's head, for example, may be substituted for the grotesque face 3. Surrounding the latter is a border or space 4 on which any appropriate advertising matter may be printed or otherwise suitably applied. This advertising matter may, if desired, extend to and partly cover the face 3.

In lieu of eyes, the face 3 is provided with two aligned oppositely disposed transparent semi-tubular housings 5, in each of which is loosely confined a relatively heavy round body 6 simulating the natural eye ball, and the latter is preferably black or dark in color. The housings 5 are formed by appropriately bending any suitable transparent and/or translucent sheet material or they may be molded from glass. In the drawing I have shown the housings made from transparent sheets of Celluloid bent to semi-tubular form and provided with side wings or flanges 14, for insertion through parallel slits 7, cut in the card 1. Gummed tapes 8 pasted to the rear face of the card 1, and over the flanges 14, hold the latter tightly against the rear face of the card. The rectangular space 15, between each pair of slits 7, on the front face of the card 1, is of a color preferably white, contrasting sharply with the round bodies or balls 6.

As previously stated the balls 6, are loosely

confined within the transparent housings 5, in such manner that they may freely roll from end to end or from top to bottom of the casings. Such movement is caused by the vibration set up incident to the running, starting and stopping of the vehicle in which the advertising card is displayed. Escape of the balls from the open ends of the housings is prevented by transparent tabs 9 which extend across these open ends and serve as stops for the balls as they roll to and fro. These tabs are flexible or slightly resilient and thus tend to promptly reverse the movement of the balls under impact. The tabs 9 are formed with flanges 10 adapted to be inserted through small slots 11 and secured to the back of the card 15 by gummed strips 12.

The housings are horizontally disposed and the relatively heavy balls are nicely balanced therein so that minor vibrations or slight tilting of the vehicle from the horizontal will cause the balls 20 to move. This movement of the balls from side to side and top to bottom, of the contrasting colored background spaces 15, immediately attracts the attention of the passengers to the goods of the advertiser, described in advertising space 4. 25 The light colored spaces 15 simulate the whites of the eyes and help in increasing the animation produced by the rolling balls.

Having thus described my invention, what I claim is:

1. An advertising device comprising a card of relatively stiff material, the front of said card bearing the representation of a face, said face having eye areas, a pair of transparent housings mounted on said face over the eye areas thereof, and ball like members loosely mounted for rolling movement in said housings.

2. An advertising device comprising a card of relatively stiff material, the front of said card bearing the representation of a face, said face having eye areas, a transparent housing mounted on said card over one of said areas, and ball like member mounted for rolling movement in said housing.

3. An advertising device comprising a card of relatively stiff material, the front of said card bearing the representation of a face, said face having eye areas, a pair of transparent housings mounted on said face over the eye areas thereof, and ball like members loosely mounted for rolling movement in said housings, said ball like members and said eye areas being contrastingly colored.

4. An advertising device comprising a card of relatively stiff material, the front of said card

bearing the representation of a face, said face having eye areas, a transparent housing mounted on said card over one of said areas, and ball like member mounted for universal movement in said housing.

5. An advertising device comprising a card of relatively stiff material, the front of said card bearing the representation of a face, said face having colored eye areas, a pair of transparent

10 housings mounted on said face over the eye areas thereof, and colored ball like members loosely mounted for rolling movement in said housings.

6. An advertising device comprising a card of 15 relatively stiff material, the front of said card bearing the representation of a face, said face having eye areas, a transparent housing mounted on said card over one of said areas and open at both ends, and ball like member mounted for 20 universal movement in said housing, and stop means adjacent said open ends limiting lateral movement of said ball like member.

7. An advertising device comprising a card of 25 relatively strong material, the front of said card bearing the representation of a face, said face having eye areas, slots on opposite sides of said areas, housings bent into semitubular form from sheets of transparent material, said housings having side flanges inserted through said slots, 30 means for holding said flanges substantially flat against the rear face of the card and spherical members freely movable in said housings.

8. An advertising device comprising a card of relatively stiff material, the front of said card bearing the representation of a face, said face having eye areas, a transparent housing mounted on said card over one of said areas and open at 5 both ends, and ball like member mounted for universal movement in said housing, and flexible stop means adjacent said open ends limiting lateral movement of said ball like member.

9. An advertising device comprising a card of 10 relatively stiff material, the front of said card bearing the representation of a face, said face having eye areas, a pair of transparent housings open at their ends and mounted on said face over the eye areas thereof, and ball like members 15 loosely mounted for rolling movement in said housings, said ball like members and said eye areas being contrastingly colored and transparent stop members for preventing escape of said ball like members through said open ends. 20

10. An advertising device for vehicles comprising a card of relatively strong material, the front of said card bearing the representation of a face associated with advertising matter, said face having eye areas, transparent housings 25 mounted over said areas, loosely mounted members in said housings adapted to move to and fro in said casing under the vibratory and tilting action of the moving vehicle in which the card is mounted.
